UNITED STATES PATENT OFFICE

153,115

DESIGN FOR A CIGARETTE ASH TRAY UNIT

Kenneth L. Childs, New Haven, Conn., assignor
to Ken Childs, Inc., New Haven, Conn., a cor-
poration of Connecticut

Application April 28, 1947, Serial No. 138,664

Term of patent 3½ years

(Cl. D85—2)

To all whom it may concern:

Be it known that Kenneth L. Childs, a citizen of the United States, residing at New Haven, in the county of New Haven and State of Connecticut, have invented a new, original, and ornamental Design for a Cigarette Ash Tray Unit, of which the following is a specification, reference being had to the accompanying drawing, forming part thereof.

In the drawing:

Fig. 1 is a front perspective view of a cigarette ash tray unit, showing my new design; and

Fig. 2 is a perspective view of one of the cigarette ash trays of Fig. 1, all of the ash trays being substantially the same.

I claim:

The ornamental design for a cigarette ash tray unit, substantially as shown.

KENNETH L. CHILDS.
